214,301

SOCK

Edward M. Clark, Greensboro, N.C., assignor to Kiddie Tot Hosiery Mills, Inc., High Point, N.C., a corporation of North Carolina

Filed Jan. 25, 1968, Ser. No. 10,311

Term of patent 14 years

Int. Cl. D2—04

U.S. Cl. D2—334

FIG. 2

FIG. 3

FIG. 1 is a side elevational view of a sock showing my new design, the side opposite being reversely similar; FIG. 2 is an enlarged fragmentary view thereof; and FIG. 3 is an enlarged sectional view taken on the line 3—3 of FIG. 1.

I claim:

The ornamental design for a sock, as shown and described.
